PAPER ARTICLE

Application filed October 22, 1928. Serial No. 314,039.

This invention relates to improvements in paper articles.

It is the object of the invention to provide a novel and improved means for imparting desired designs to paper articles such as doilies, shelf paper, paper napkins, paper containers, etc.

The invention has to do with certain definite means of combining the use of embossing and color. I am well aware that paper articles have been embossed and have also been colored but it is my purpose to provide a means for causing designs to stand out on a paper article more conspicuous than has heretofore been possible due to the particular manner in which embossing and color are employed and corrugated to produce the desired design.

In the drawings:

20 Figure 1 is an enlarged detail fragment of a design embodying this invention.

Figure 2 is a section taken on line 2—2 of Figure 1.

Like parts are identified by the same reference characters throughout the several views.

The suggestion of texture given to the body 25 of the article is shown diagrammatically at 6, it being understood that the small squares shown at 6 will be reproduced to cover the 30 entire surface of the body portion of the article except as hereinafter designated. These small squares are made by very fine intersecting ribs 7 which will be apparent both in Figure 1 and in Figure 2. It is not essential that 35 the ribs should intersect to produce the desired result since it is well known to those skilled in this art that fine embossing may be used in a variety of ways to impart texture to the body of a paper article. See for example the ribs illustrated in my design application relating to a paper napkin No. D. 40 26,434.

One of the characteristics and outstanding features of the present invention consists in 45 the substantial omission of all texture embossing from the area 8 which is shaped to represent a flower or other desired figure and is outlined by a series of short and relatively heavily embossed ridges 9. Other heavily 50 embossed ridges may be used, if desired, at 10

to suggest the structure of the flower but the surface 8 is generally free of all embossing and comprises a plane surface to which color may be applied either by dye or paint in order to render surface 8 in extremely high contrast 55 to the body portion 5 of the paper article.

At 11 I have shown an elongated and relatively highly embossed pair of ridges which correspond to flower stems or may be used in any design other than a floral design to tie 60 together the various parts of the design. These stems may also be colored if desired.

One possible combination consists in the use of a pinkish or lavender shade applied to the area 8 as suggested by the shade lines 65 thereon while the ribs 11 may be colored green, as likewise indicated by the shading. It is particularly to be noted that in accordance with this invention the coloring is preferably restricted to the plane or unembossed 70 areas 8 and 11. The unembossed areas 9 and those shown at 10 may be colored or left uncolored as desired, but one of the features of the invention consists in the association of 75 color contrast in aid of the contrast between embossed and unembossed portions of the article, whereby the contrast between such portions is made apparent not only by texture but also by color.

I claim:

A paper article having a portion embossed in simulation of texture, on an intermediate part of which appears a portion having no texture embossing and of predetermined design, said last mentioned portion being surrounded by short heavily embossed ribs whose general direction is transverse to the line of demarcation between the portions embossed for texture and the last mentioned portion which is unembossed for texture, the respective portions being in color contrast in a pattern registering with the line of demarcation between said portions as determined by said heavily embossed ribs.
